UNITED STATES PATENT OFFICE.

JOHN W. BIRKENSTOCK, OF NEW YORK, N. Y., ASSIGNOR, BY DIRECT AND MESNE ASSIGNMENTS, TO THE EMPIRE PNEUMATIC TOOL COMPANY OF THE STATE OF NEW YORK, OF NEW YORK, N. Y.

PNEUMATIC CUTTING-TOOL.

SPECIFICATION forming part of Letters Patent No. 691,334, dated January 14, 1902.

Application filed May 7, 1901. Serial No. 59,140. (No model.)

To all whom it may concern:

Be it known that I, JOHN W. BIRKENSTOCK, a citizen of the United States, residing in New York, borough of Manhattan, in the State of New York, have invented certain new and useful Improvements in Pneumatic Cutting-Tools, of which the following is a specification.

This invention relates to an improvement in pneumatic cutting-tools to which reciprocating motion is imparted in imitation of the motion imparted by a mallet, said cutting-tool being so constructed that the supply of compressed air can be instantly interrupted, so as to stop or start the tool as required; and the invention consists of a pneumatic cutting-tool comprising a cylinder; a reciprocating piston in said cylinder provided with a hammer, a handle attached to said cylinder and provided with a lever-operated valve for admitting air under pressure or shutting it off, a tubular slide-valve provided with abutments operated by the piston, ports for admitting air to the chambers at either end of the piston, and outlet-ports in the cylinder.

The invention consists, further, of certain details of construction and combinations of parts which will be fully described herein-after and finally pointed out in the claims.

In the accompanying drawings, Figure 1 represents a side elevation of my improved pneumatic cutting-tool. Figs. 2 and 3 are vertical longitudinal sections of the same, showing the slide-valve in its primary and secondary positions, so as to illustrate the forward-and-backward motion of the piston. Fig. 4 is a vertical transverse section on line 4-4, Fig. 3; and Fig. 5 is a detail section of the slide-valve operated by the piston.

Similar letters of reference indicate corresponding parts.

Referring to the drawings, A represents a cylindrical casing, which is closed at the rear end by a head B, provided with a suitable handle B'. The bow-shaped handle is provided with a longitudinal recess, in which is arranged a fulcrumed lever C, which is provided with a thumb-piece or button C' at its upper end for moving the lever in backward direction when it is desired to shut off the

supply of compressed air or in the opposite direction to admit air. The lower end of the bow-shaped handle is connected by a tubular channel B² with the head B, said channel being controlled by means of a hollow slide-valve D, which is acted on by a knuckle C² on lever C, said valve having a port d, that may be placed in register with the inclined channel B² when compressed air is to be supplied to the tool, but which at the outward movement of the lever is moved in upward direction by the pressure action of the compressed air, so as to place the inlet-port d out of register with the inclined channel B² when the supply of compressed air is to be interrupted. The lower tubular end of the handle B' is connected by a suitable coupling e with the supply-pipe E for compressed air in the well-known manner. The opposite end of the cylindrical casing A is closed by a guide-disk a and provided with a projecting stationary sleeve A', screwed into the head of the casing, as shown in Figs. 2 and 3. In the guide-sleeve A' is placed the polygonal shank of the cutting-tool T, the interior of the sleeve being made to fit to said shank, so as to guide the same and prevent its axial turning. In the casing A is arranged an interior cylinder a', in the bore of which is guided a piston F, which is provided at the end adjacent to the tool-shank with a hammer-like extension F', so as to strike the end of the tool-shank by the reciprocating motion of the piston. The air is admitted alternately into the opposite ends of the interior of the cylinder by means of a tubular sectional slide-valve G, which is guided in a bore a² of the cylinder and head B, said slide-valve being inserted through the corresponding channel in the head, which is then closed by means of a screw-plug g. The slide-valve G is provided at opposite ends with lugs g', that project into the path of the piston, so as to be operated by the piston when it is moved in one or the opposite direction. Adjacent to the lugs g' the tubular slide-valve G is provided with ports p p' for the admission of compressed air, said ports communicating with channels a³ in the solid portion of the cylinder a', which chan-

nels communicate with the spaces at the opposite ends of the cylinder. The outlet-ports are indicated by a^4 a^5 . The cylinder is provided below the piston F with a recess R, in which is located an interiorly-threaded sleeve r, by which the two sections of the tubular slide-valve G are connected together and by which, owing to the difference in the threads of the sections, the adjustment of the sections 10 toward or away from each other is permitted. The polygonal head r' at one end of the adjusting-sleeve r provides for the convenient adjustment of the same by means of a suitable wrench. By the adjustment of the sections 15 of the slide-valve the lugs g' are moved farther apart or closer together, whereby the stroke of the piston can be regulated within certain limits.

The operation of my improved hammer or 20 cutting-tool is as follows: The lever C is moved inwardly into the handle B', so that the port d of the valve operated thereby is placed in line with the inclined supply-channel B². The air under pressure then passes through one 25 end of the tubular slide-valve G and through one port—say p, Fig. 2—into the chamber located at one end of the piston F, so as to immediately force the piston forward and cause the same to strike by its hammer a blow on 30 the shank of the tool T. By the forward motion of the piston the lug at the opposite end of the slide-valve is struck by the piston and the slide-valve shifted, so that the supply of air through the port p is interrupted, while the opposite port p' is opened and air under pressure admitted into the 35 annular chamber around the hammer F'. The action of the air moves the piston back into its former position against the first lug, so 40 as to shift the slide-valve back again into its initial position ready to receive the entire supply of compressed air at this end, which produces another forward stroke of the piston, and so on. As the piston abuts 45 against the lugs, it never can fully move up to the ends of the cylinders, and hence the chambers at each end of the cylinders serve 50 for cushioning the piston. The air in the cylinder is permitted to escape at the end of each stroke through the ports at a^4 a^5 , arranged in the lower solid portion of the cylinder, one at each side of the slide-valve, said ports permitting the air to escape, so that no counteracting pressure is exerted on the 55 piston during the return motion of the same.

When the motion of the tool is to be interrupted, by letting go of the lever in the handle the pressure of the air in tubular slide-valve D, which admits the air, will force the valve upward and lever backward, as shown 60 in Fig. 1, so that the slide-valve D for the compressed air is shifted and its port connection d with the inclined channel B² interrupted, the motion of the tool being restored under the action of the compressed air 65 as soon as the lever is returned into position in the handle, as shown in Figs. 2 and 3. By taking hold of the handle the tool can be applied in any desired position to the work in hand, and thereby the cutting of stone and 70 other work performed in a very quick and effective manner.

Having thus described my invention, I claim as new and desire to secure by Letters Patent—

1. A pneumatic cutting-tool, consisting of a cylinder, a recessed handle suitably attached to said cylinder, a valve for admitting air under pressure, a lever for operating said valve and located in the recess of said handle, a piston in the cylinder, provided with a hammer for actuating the tool, a tubular slide-valve provided with lugs projecting into the path of the piston, ports for supplying compressed air alternately to each end of the 85 cylinder, and suitable outlet-ports, substantially as set forth.

2. A pneumatic cutting-tool, consisting of a cylinder, a box-shaped handle suitably applied to one end of the cylinder, a supply-channel in said handle, a controlling-valve, means for operating the said valve for admitting or shutting off the compressed air, a piston in said cylinder provided with a hammer, a fixed sleeve for guiding the tool, a tubular slide-valve provided with lugs engaged by said piston, ports in said slide-valve communicating with said supply-channel for admitting air into the ends of the cylinder, means for adjusting the tubular slide-valve, 95 and outlet-ports in the cylinder, substantially as set forth.

In testimony that I claim the foregoing as my invention I have signed my name in presence of two subscribing witnesses.

JOHN W. BIRKENSTOCK.
